SHOE

Mollie Gordon, Philadelphia, Pa., assignor to
Reuben Gordon Shoe Co., Inc., Philadelphia,
Pa., a corporation of Pennsylvania

Application May 29, 1950, Serial No. 10,252

Term of patent 3½ years

(Cl. D7—7)

To all whom it may concern:

Be it known that I, Mollie Gordon, a citizen of the United States and a resident of Philadelphia, county of Philadelphia, State of Pennsylvania, have invented a new, original, and ornamental Design for a Shoe, of which the following is a specification, reference being had to the accompanying drawings, forming a part thereof, wherein:

I claim:

The ornamental design for a shoe, substantially as shown.

MOLLIE GORDON.
